DESIGN FOR A DOLL

Irene Alma Edensburn, Chicago, Ill.

Application October 4, 1945, Serial No. 122,527

Term of patent 7 years

(Cl. D34—4)

To all whom it may concern:

Be it known that I, Irene Alma Edensburn, a citizen of the United States, residing at Chicago, in the county of Cook and State of Illinois, have invented a new, original, and ornamental Design for a Doll, of which the following is a specification, reference being had to the accompanying drawing, forming a part thereof.

In the drawing:

Fig. 1 is a front view of a doll embodying my new design;

Fig. 2 is a side view; and

Fig. 3 is a rear view.

I claim:

The ornamental design for a doll, substantially as shown.

IRENE ALMA EDENBURN.
